SCRAPER

Josef A. Disse, Detroit, Mich.

Application September 13, 1943, Serial No. 502,231

11 Claims. (Cl. 30—315)

The invention relates to scrapers of that type usually employed in the truing of metal surfaces and for like purposes.

It is the object of the invention to obtain a construction in which the scraping tool forms a relatively small part of the structure which, however, is firmly attached to the operating handle and can be removed or replaced whenever necessary.

The invention therefore consists in the construction as hereinafter set forth.

In the drawing:

Figure 1 is a plan view of my improved scraper. Figure 2 is a central longitudinal section on line 2—2, Figure 1.

Figure 3 is a sectional side elevation showing the scraping tool disengaged from the handle.

Figure 4 is a perspective view of the scraping tool.

Figure 5 is a plan with the scraping tool detached illustrating a modified construction.

Figure 6 is a perspective view of the tool construction shown in Figure 5.

Figure 7 is a longitudinal section illustrating a modified construction of locking means for the tool.

My improved scraper consists essentially of a handle A and connected shank portion B forming the greater part of the length of the instrument, and an attachable tool C adapted to be rigidly connected to said shank. The tool member C is formed of a high-grade steel or other suitable cutting metal and, as shown in Figure 2 and Figure 4, has a blade portion C' of sufficient length to provide for successive sharpenings and an offset portion C² for connecting with the handle shank. Between these portions is a connecting shoulder portion C³ which abuts against the end of the shank B to transmit all work stresses thereinto. The shank B has a forwardly projecting finger portion B' which passes through a channel in the portion C³ and bears against the upper side of the portion C'. The offset portion C² bears against the upper face of the shank B and is held in firm contact therewith by a locking member D. This member is formed with a return bent hook D' at its forward end for engaging a recess C⁴ in the portion C³. There is also a pivotal toggle link D² connected to the rear end of the member D and also to the shank B, being adapted to draw the hook D' rearward and to hold the portion C² down upon the shank. The link D² has an operating portion D³ which in the position shown in Figure 2 rests upon the top of the shank, with the pivotal portion of the link located in a recess B² in said shank. In such position, the tool C is rigidly secured to the shank B and functions the same as if formed integral therewith. However, by lifting the operating portion D³, the

link D² will be swung outward, carrying the member D with it and disengaging the hook D' from the recess C⁴. Thus, the tool may be easily removed and replaced, and when worn out, a new tool may be substituted therefor.

The modified construction illustrated in Figure 5 and Figure 6 is similar to the construction previously described, with the exception that in the former the channel C⁵ for receiving the finger B' is in the center of the portion C³, whereas in the modified construction a pair of spaced fingers B³ engage channels C⁶ upon opposite sides of the portion C³ which is in the center. The locking will be just the same and will secure the tool rigidly to the shank B.

One important advantage of the construction is that the stress produced by the scraping action is transmitted directly from the blade C' into the abutting handle shank B. This avoids any tendency for the blade to spring out of shape when being used. Also the fact that the offset portion C² is held down upon the shank B and that the finger B' or fingers B³ press down upon the blade portion C', will prevent any flexing of the tool at the joint between the same and the handle shank.

The tool forms only a small portion of the instrument, so that when made of high-grade metal its costs will not be excessive.

Figure 7 illustrates a modified construction of locking means for the tool in which there is substituted for the return bent hook D' an adjustable screw D⁶ having a threaded engagement with an angle portion D⁶ on the member D. This permits of adjustment to compensate for any wear and insures that the tool will always be held firmly in abutting engagement with the shank.

Another very important advantage of the construction is that the portions C' and C² of the tool are exchangeable in positions so that either one may be used for the scraping edge. This doubles the life of the tool and also permits of having scraping edges formed of a different character on the two portions C' and C². It is also possible to form these scraping edges of any desired contour not necessarily straight. This is for the reason that the thrust of the tool is taken into the shank through the shoulder portion C³.

A still further advantage of the construction is that the scraping edge may be the full width of the tool and there is nothing in the handle or locking means projecting beyond this width. Consequently, the operator may scrape a surface in the work extending into a corner without interference.

What I claim as my invention is:

1. A scraper comprising a handle provided with a forwardly extending shank and a tool detachably engaging said shank, said tool being

formed with a blade portion and an offset securing portion, the blade portion abutting against said shank to transmit working stresses thereinto, and the offset portion being clamped to said shank.

2. A scraper comprising a handle provided with a forwardly extending shank and a tool detachably engaging said shank, said tool being formed with a blade portion and an offset securing portion, the blade portion abutting against said shank to transmit working stresses thereinto, and the offset portion being clamped to said shank, and a finger projecting from said shank through a channel in said tool to overlap the blade portion thereof.

3. A scraper comprising a handle provided with a forwardly extending shank and a tool detachably engaging said shank, said tool being formed with a blade portion, a securing portion offset into a parallel plane, and a portion connecting said blade portion and securing portion forming a shoulder for abutting against the end of said shank, said connecting portion having a channel therethrough, a finger projecting from said shank through said channel to overlap and bear against said blade portion, and clamping means for holding said connecting portion against said shoulder and said securing portion against the upper face of said shank.

4. A scraper comprising a handle provided with a forwardly extending shank and a tool detachably engaging said shank, said tool being formed with a blade portion, a securing portion offset into a parallel plane and a connecting portion between said blade and securing portions forming a shoulder for abutting against the end of said shank and having a channel formed therethrough, a finger projecting from said shank to extend through said channel to overlap and abut against said blade portion, and locking means comprising a member having a return bent hook at its forward end for engaging a recess in said connecting portion, and a toggle link pivotally connecting the rear end of said member to said shank, said toggle link when turned into its folded position occupying a recess in said shank.

5. A scraper comprising a handle provided with a forwardly extending shank and a tool detachably engaging said shank, said tool being formed with a blade portion, a securing portion offset into a parallel plane and a connecting portion between said blade and securing portions forming a shoulder for abutting against the end of said shank and having a channel formed therethrough, a finger projecting from said shank to extend through said channel to overlap and abut against said blade portion, and locking means comprising a member having a return bent hook at its forward end for engaging a recess in said connecting portion, and a toggle link pivotally connecting the rear end of said member to said shank, said toggle link when turned into its folded position occupying a recess in said shank, and an operating portion of said toggle link for turning the same resting against said shank in the locked position of said locking means.

6. A scraper comprising a handle provided with a forwardly extending shank and an attachable tool, the latter being formed with a blade portion, a securing portion offset into a parallel plane, and a connecting portion forming a shoulder for abutting against the end of said shank, said con-

nnecting portion having a central recess extending therethrough, said shank having a forwardly projecting finger passing through said recess to overlap and bear against said blade portion, and clamping means for engaging said securing portion to hold the same against the top of said shank and to hold said shoulder against the end of said shank.

7. A scraper comprising a handle provided with a forwardly extending shank and an attachable tool, the latter being formed with a blade portion, a securing portion offset into a parallel plane, and a connecting portion forming a shoulder for abutting against the end of said shank, said connecting portion having channels therethrough on opposite sides of the center thereof, a pair of spaced fingers projecting forward from said shank and passing through said channels to overlap said blade portion, and clamping means for engaging said securing portion to hold the same against the upper face of said shank to also hold said shoulder against the end of said shank.

8. A scraper comprising a handle provided with a forwardly extending shank, a tool detachably engaging said shank, said tool having offset opposite end portions, either one or both of which form scraping edges being also provided with an intermediate shoulder portion for abutting against said shank to transmit working stresses thereinto, and means for clamping the rearwardly extending offset portion to said shank.

9. A scraper comprising a handle provided with a forwardly extending shank, a tool detachably engaging said shank, said tool being formed with oppositely extending offset end portions with a shoulder portion therebetween, and means for clamping said tool with one of said offset portions overlapping said shank and with said shoulder portion abutting against the end of the shank, said clamping means including a return bent hook engaging said shoulder portion and adapted to draw the same into abutting engagement with said shank.

10. A scraper comprising a handle provided with a forwardly extending shank, a tool detachably engaging said shank having oppositely extending offset portions with a shoulder portion therebetween, one of said offset portions being adapted to overlap said shank with the shoulder portion abutting against the end of the shank, and locking means for said tool comprising a toggle lever pivotally connected to said shank and overlapping the portion of the tool overlapping the shank, the free end of said toggle lever having a hook portion for drawing said shoulder portion of the tool into abutting engagement.

11. A scraper comprising a handle provided with a forwardly extending shank, a tool detachably engaging said shank having oppositely extending offset portions with a shoulder portion therebetween, one of said offset portions being adapted to overlap said shank with the shoulder portion abutting against the end of the shank, and locking means for said tool comprising a toggle lever pivotally connected at its rear end to said shank and extending over said overlapping portion of the tool, the forward end of said toggle having an angle portion overlapping said shoulder portion and an adjustable bearing on said angle portion for engaging said shoulder portion whereby the latter may be drawn by said toggle lever into abutting engagement with the shank.
